(57) **CLAIM**

The ornamental design for a table mount for flat panel electronic display, as shown and described.

DESCRIPTION

FIG. 1 is a right side view of our design for a table mount for flat panel electronic display;

FIG. 2 is a rear view thereof;

FIG. 3 is a front view thereof;

FIG. 4 is a left side view thereof;

FIG. 5 is a bottom view thereof;

FIG. 6 is a front perspective view thereof; and,

FIG. 7 is a top view thereof.

The broken lines shown on the drawings is included for the purpose of illustration and forms no part of the claimed design.
